UNITED STATES PATENT OFFICE.

WEBSTER L. MARBLE, OF GLADSTONE, MICHIGAN.

REAR SIGHT.

982,151.

Specification of Letters Patent. Patented Jan. 17, 1911.

Application filed July 1, 1909, Serial No. 505,455. Renewed June 24, 1910. Serial No. 568,715.

To all whom it may concern:

Be it known that I, WEBSTER L. MARBLE, a citizen of the United States, residing at Gladstone, in the county of Delta and State 5 of Michigan, have invented new and useful Improvements in Rear Sights, of which the following is a specification.

This invention relates to sights for firearms, and its object is to improve what are 10 known as flexible vertically-adjustable rear sights.

To this end the invention consists in certain features of construction and arrangement whereby the spring joint is made more 15 simple and at the same time stronger, and also in a simple mode of changing the size of the peep hole in the target of the sight, all as hereinafter set forth and particularly pointed out in the claims.

20 In the accompanying drawings, Figure 1 is a side elevation of the sight. Fig. 2 is a sectional side view. Fig. 3 is a cross section on the line 3—3, Fig. 2. Fig. 4 is a rear view of the target and its shank. Fig. 5 is a front elevation of the same. Fig. 6 is a 25 vertical section thereof. Fig. 7 is a top plan view, and, Fig. 8 is an exploded perspective view.

The base plate 1 has two ears 2 between 30 which is received the knuckle 3 of the standard 4. A pivot or pintle 5 passes transversely through the ears and knuckle, having at one end a head 6 and at the other end screw threads to receive the retaining nut 7.

35 A dowel pin 8 on the head enters one of two or more sockets 9 in the ear to prevent the pintle from turning, and to enable it to be angularly adjusted. The standard is intended to stand vertical when the gun is

40 held in a horizontal firing position, and this brings it at an oblique angle to the base plate. In order to permit the base plate to be secured to stocks having different slopes, and yet have the standard vertical, 45 the pintle is made angularly adjustable by causing the dowel pin to enter the proper socket in the ear.

The knuckle is slotted or bifurcated to receive the free end of a strong U-shaped leaf 50 spring 10, similar to the sear spring of a gun lock. The lower member of said spring is seated in a longitudinal groove in the base plate, while its upper free member extends through the knuckle and bears upwardly against the same. The pintle is flattened or cut away to permit the spring

to occupy a position along or above a diameter of the pintle, so that the action of the spring is to return the standard to its upright position even if it is folded down flat 60 upon the base plate; the reason being that the point at which the spring bears against the knuckle in either of these positions is at one side of the center of the pintle, so that the spring always can effect a turning movement with respect to said pintle, and inasmuch as the bearing point is always between the center of the pintle and the target of the sight, the result is to lift said target to its operative position. 70

If it is desired to lock the standard in either of its folded down positions, as indicated in dotted lines in Fig. 1, a small bolt 11 in the knuckle can be dropped into a socket 12 in one side or the other of the ear 75

2. The bolt has a head by means of which it can be lifted out of said socket when the standard is to be released. In the standard 4 is supported the shank 13 of the peep sight. For convenience of manufacture, the target 80

14 is made separate from its shank. On the front of the target is a boss 15 having a wide upright groove with undercut walls. The shank has a head 16 provided with dovetail flanges 17 to fit said groove and thereby secure the target to said shank. In order to lock the target from coming off, it carries preferably a spring latch 18 which takes under the lower edge of the head 16 when the target has been slid down into place. 90 To release the target, the spring can be pressed back to the position shown in dotted lines in Fig. 7, out of line with the head 16.

The target has the usual peep hole 19, but in order to vary the effective opening of 95 said hole, I provide the head with two or more slides containing holes of different sizes and adapted to be brought in line with the peep hole 19 when desired. These slides

20 are preferably arranged to move vertically, being superposed one behind the other, in an upright slot in the head 16. Each slide has flanges 21 fitting the flattened sides of the head, and said flanges are preferably roughened to give a finger hold. 100

A screw stud 22 is fixed in the upper part of the head above said slides, crossing the slot, and having a nut 23 by means of which the two portions of the head on either side of the slot can be pinched together, thereby 110 clamping the slides and locking them in place, wherever they may be in said slot.

In each slide is an aperture 24, one being smaller than the other, and both being smaller than the peep hole 19. The head 16 has a hole 25 in line with the peep hole 19, so that by moving one or the other of the slides down until its aperture comes in line with said peep hole, the effective size of said hole will be lessened. When the slides are both in their upper positions, the view 10 through the hole 19 is unobstructed. The shank has the usual toothed wings 26 for enabling it to be vertically adjusted in the standard of the sight, by means of the rotatable screw sleeve 27.

15 Having thus described my invention, what I claim is:

1. A rear sight having a base plate, a standard having a bifurcated knuckle, a pintle cut away to its center, and a leaf 20 spring passing through said knuckle and bearing against the same on each side of said pintle.
2. A rear sight, having a peep hole, and a plurality of superposed slides having perforations of different sizes adapted to be brought in line with said hole to vary its effective size.
3. A rear sight having a shank provided with a slot, and a plurality of superposed 25 slides having perforations of different sizes and movable in said slot.

4. A rear sight having a shank provided with an upright slot, and superposed slides having perforations of different sizes and movable up and down in said slot. 35

5. A rear sight having a shank provided with an upright slot, superposed perforated slides independently movable up and down in said slot, and means for clamping said slides. 40

6. A rear sight having a head provided with an upright slot, a target sight secured to said head and having a peep hole, and perforated slides movable in said slot into and out of line with said peep hole, said 45 slides having roughened flanges.

7. A rear sight having a shank provided with a dovetail head, and a target peep sight provided with a boss having an under cut groove to engage with said head. 50

8. A rear sight having a shank provided with a head, a target peep sight having a groove to engage with said head, and a spring latch for securing said target to said head. 55

In testimony whereof I have signed my name to this specification in the presence of two subscribing witnesses.

WEBSTER L. MARBLE.
